UNITED STATES PATENT OFFICE

2,164,856

PIPE CLEANER

Maurice Francis Lyons and Brand Kaplan, Cincinnati, Ohio, assignors, by direct and mesne assignments, of one-half to Murray E. Haddon, Chicago, Ill.

Application March 18, 1937, Serial No. 131,744

8 Claims. (Cl. 131—13)

This invention relates to a pipe cleaner, and it is primarily an object of the invention to provide a device of this kind which can be employed with advantage in cleaning either the stem or the neck portion of a pipe.

It is also an object of the invention to provide a device of this kind comprising an elongated strand of material surrounded by a spun cleaning fabric together with an enlargement carried by an end portion of the strand, said enlargement being of yieldable material and also covered with a spun cleaning fabric, said enlargement being particularly designed for the cleaning of the neck of the bowl of the pipe while the remaining portion of the device is intended for insertion through the stem.

The invention consists in the details of construction and in the combination and arrangement of the several parts of our improved pipe cleaner whereby certain important advantages are attained and the device rendered simpler, less expensive and otherwise more convenient and advantageous for use, as will be hereinafter more fully set forth.

25 The novel features of our invention will hereinafter be definitely claimed.

In order that our invention may be the better understood, we will now proceed to describe the same with reference to the accompanying drawings, wherein:

30 Figure 1 is an elevational view of a pipe cleaner constructed in accordance with an embodiment of our invention;

Figure 2 is an enlarged fragmentary view in section of the end portion of the device provided with the enlargement;

Figure 2a is an enlarged sectional view taken through the upper portion of Figure 2.

Figure 3 is a sectional view taken substantially on the line 3—3 of Figure 1;

Figure 4 is a fragmentary view illustrating another embodiment of our invention;

Figure 5 is a fragmentary sectional view illustrating still another embodiment of the invention;

Figure 6 is a fragmentary sectional view illustrating an additional embodiment of the invention;

Figure 7 is a fragmentary sectional view illustrating another embodiment of the invention;

Figure 8 is a fragmentary sectional view illustrating a still further embodiment of the invention.

Our improved pipe cleaner as herein disclosed

55 comprises an elongated cylindrical strand of wire

1 of desired gauge and approximately eight inches in length. Adjacent to one end the strand 1 is surrounded by an enlargement 2 in the form of a truncated cone with its smaller end disposed outwardly toward the adjacent end of the strand or wire 1. This enlargement 2 is made of suitable yielding material, such as sponge rubber, although we do not wish to be understood as limiting ourselves to this particular material. The strand of wire 1 together with the enlargement 2 are cased by a lamination 3 of suitable spun fabric. This lamination 3 is also an absorbent material whereby the desired cleaning action of the device is materially facilitated.

In practice, the cased enlargement 2 is employed to clean out the neck portion of a pipe while the cased portions of the wire strand 1 are used for cleaning out the stem of the pipe. The cased portion of the strand of wire 1 in advance of the enlargement 2 is particularly intended for insertion through the port or channel which connects the neck of a pipe directly with the bowl.

In lieu of a single strand of wire there can also be employed, as illustrated in Figure 4 of the drawing, two wires 1' of requisite gauge wrapped or twisted one around the other. The strands of the lamination 3' surrounding the strand 1' will interlock therewith as permitted by the resilient spiral peripheral channel resulting from the twisting of the wires.

In the embodiment of our invention as illustrated in Figure 5, the enlargement 2'' is entirely made of woven or spun strands similar to those comprised in the spun or woven lamination 3'' with said enlargement 2'' and lamination 3'' being permanently connected although, as illustrated in Figure 6, the enlargement 2a may be formed separately from the lamination 3a.

In the invention as illustrated in Figure 7 at a point in close proximity to the enlargement 2b the lamination 3b is cut away to bore for a short distance the strand or strands 1b so that when desired a person may readily break off the strand or strands 1b at this bared part 4 so that the major portion of the strand or strands 1b will be separated from the enlargement 2b whereby the stem cleaner may be drawn completely through the stem of the pipe.

In Figure 8 is illustrated an embodiment of our invention wherein the enlargement 2c is hollow but covered with a lamination 3c of desired woven material possessing desired qualifications. This enlargement 2c is preferably of rubber and has its smaller end portion solid, as at 5, for a

55

considerable distance, said portion 5 being of rubber through which the strand or strands 1^c are pinioned. In this embodiment of the invention the enlargement 2^c can be freely introduced and removed with respect to various size bores in the neck portions of pipes and by having the solid rubber portion 5 this enlargement 2^c does not have to be interwoven, or otherwise positively connected to the strand or strands 1^c.

10 From the foregoing description it is thought to be obvious that a pipe cleaner constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the 15 precise arrangement and formation of the several parts herein shown in carrying out our invention in practice except as hereinafter claimed.

We claim:

1. A pipe cleaner comprising an elongated strand, an enlargement of yielding material surrounding the strand adjacent to an end thereof, and a lamination of woven fabric casing the strand and the enlargement, the lamination being so constructed and applied as to allow disjoinder of the enlargement on the strand from the remaining portion of the strand.
2. A pipe cleaner comprising an elongated strand, an enlargement of yielding material surrounding the strand adjacent to an end thereof, and a lamination of woven fabric casing the strand and the enlargement, the strand interlocking with the material of the enlargement and the lamination.
3. A pipe cleaner comprising an elongated strand, an enlargement of yielding material surrounding the strand adjacent to an end thereof,

and a lamination of woven fabric casing the strand and the enlargement, the enlargement being hollow and having a solid end portion through which the strand is pinioned.

4. A pipe cleaner comprising an elongated strand, an enlargement of yielding material surrounding the strand adjacent to an end thereof, and a lamination of woven fabric casing the strand and the enlargement, said strand comprising wires twisted one about the other and engaging the material of the enlargement and the lamination.

5. A pipe cleaner comprising an elongated strand, and a lamination of woven fabric casing the strand, one end portion of the strand having means to facilitate the use of the cleaner in a pipe neck, the lamination adjacent to the end portion carrying such means being separated to permit separation of said end portion from the remainder of the strand.

6. A pipe cleaner comprising an elongated strand carrying cleaning means, said strand at a predetermined point intermediate its ends being so constructed and arranged to permit separation of one end portion of the strand.

7. A pipe cleaner comprising an elongated strand, a yielding enlargement carried by the strand, and a lamination of woven fabric casing the strand, said lamination being so constructed and applied as to allow disjoinder of the enlargement on the strand from the remaining portion of the strand.

8. A pipe cleaner comprising an elongated strand, an enlargement of yielding material surrounding the strand, and a lamination of woven fabric casing both the strand and the enlargement, said enlargement being elongated and in the general form of a truncated cone.

MAURICE FRANCIS LYONS. 40
BRAND KAPLAN.

CERTIFICATE OF CORRECTION.

Patent No. 2,164,856.

July 4, 1939.

MAURICE FRANCIS LYONS, ET AL.

It is hereby certified that the above numbered patent was erroneously issued to the inventors, said "Lyons" and "Kaplan", as assignors, by direct and mesne assignments, of one-half to Murray R. Haddon, whereas said patent should have been issued to Brand Kaplan and Murray R. Haddon, as assignees by direct and mesne assignments of one-half interest each in said invention, as shown by the record of assignments in this office; and that the said Letters Patent should be read with this correction therein that the same may conform to the record of the case in the Patent Office.

Signed and sealed this 22nd day of August, A. D. 1939.

Leslie Frazer
